UNITED STATES PATENT OFFICE

JAMES W. CHRISTIE, OF MINNEAPOLIS, MINNESOTA

FURNACE

Application filed May 31, 1929. Serial No. 367,202.

My invention relates to furnaces, and more particularly to furnaces intended for burning fine coal. An object of the invention is to provide means for causing the fire to burn up quickly in the morning when the furnace is charged with fresh fuel, and for securing more perfect combustion of fuel than is attained with furnaces now in common use. In the use of furnaces which are extensively employed, the fire is slow in starting up in the morning after being banked for the night, and furthermore only an imperfect combustion of the fuel is obtained so that a considerable percentage of the gaseous products passes out into the air in an unconsumed condition. The result of this is that a large amount of heat is wasted and quantities of smoke and soot are discharged into the atmosphere with resultant injurious effects. In carrying out my invention, I provide a perforated baffle plate which is placed in the firebox in spaced relation above the grate and in spaced relation ahead of the rear portion of the shell of the furnace so that the gases from the coal pass through the perforations of the baffle plate into a space at the rear thereof which is just above a hot spot produced by live coal which does not become covered with fresh coal when the furnace is charged.

The full objects and advantages of my invention will appear in connection with the detailed description thereof, and the novel features of my inventive idea will be particularly pointed out in the claims.

In the accompanying drawings which illustrate a practical embodiment of my invention, Fig. 1 is a view in central vertical section showing my improved feature in combination with a furnace. Fig. 2 is a view in horizontal section on the line 2—2 of Fig. 1. Fig. 3 is a view on an enlarged scale and in vertical section through the furnace wall taken at right angles to Fig. 1. Fig. 4 is a view in horizontal section on the line 4—4 of Fig. 3. Fig. 5 is a perspective view of a modified construction.

My device is adapted to be used in connection with furnaces of well known construction and as shown in the drawings, the furnace includes a shell having inner and outer

walls 10 and 12 spaced from each other. This shell is provided with the customary charging door toward the upper portion thereof below which there is a firebox 15 and a grate 16 at the bottom underneath which there is an ashpit 18. At the upper portion of the shell, customary water chambers 20 and a smoke pipe 22 are provided. The outlet from the firebox is out of vertical alinement with the pipe or flue 22 of the furnace. As best shown in Fig. 1, a baffle plate 24 is placed in the furnace in such position as to be spaced from the rear of the shell and above the grate. As shown in Figs. 1 to 4, the baffle plate is constructed of metal and has a water passage 26 around inside of its thickened margin which prevents the plate from being burned out. Water inlet and outlet pipes 28 and 30 are connected with the water passage 26, these pipes extending out through the shell of the furnace and serving to support the baffle plate in proper position. Inside of its margin, the baffle plate consists of a thinner member 32 which is provided with a multiplicity of perforations 34 and two diagonal slots 36, these slots serving to take care of expansion and contraction. In the form shown in Fig. 5, I provide a baffle plate 38 which is made of fire-clay without any water passage and is supported within the shell of the furnace in any suitable manner. The central portion of this plate is made thinner than the margin and is provided with a multiplicity of perforations 40.

The operation and advantages of my invention will be understood in connection with the foregoing description. When the furnace has just been charged with fuel, the condition thereof is indicated in Fig. 1 in which there is a bed of live coal 42 above the ashes 44, and a charge of fresh fuel 46 above the live coal and piled up in front of the baffle plate. Air entering the ashpit takes the path of least resistance indicated by the arrows 48 and flows up through the live coal into the space back of the baffle plate. Air entering through openings in the charging door takes the path designated by the arrows 50 and since this air is cold, it follows the contour of the upper surface of the coal to the rear of

the baffle plate. Gases from the live coal follow the path indicated by the arrows 51 and pass through the perforations 34 in the baffle plate to the space at the rear thereof. 5 During the night, the coal burns down to about the position indicated by the dotted line 52. Before the furnace is charged, some of the live coal is pushed back under the baffle plate so as to produce a hot spot as indicated at 54 located at the bottom of the space at the rear of the baffle plate. This hot spot causes the gases coming from the fresh coal to be ignited in the space at the rear of the baffle plate instead of passing up in non-ignited condition to the smoke pipe. Furthermore, the provision of the baffle plate reduces the percentage of gaseous products passing from the furnace in unconsumed condition during the continued operation of the furnace. 20 The baffle plate shown in Fig. 5 being made of fire-clay or other similar highly fire-resistant material, does not need any water passage therein for its protection. In the form shown in Figs. 1 to 4, the baffle plate 25 is protected and prevented from being burned out on account of the provision of the water passage which incidentally may be used to supply hot water.

The operation and advantages of my invention may be summarized as follows:

1. It provides a construction whereby all the gases are burned as they accumulate.
2. It permits the burning of the smaller sizes of anthracite coal such as nut and pea mixed, pea, buckwheat or rice, without fear of explosion even though the coal should contain a considerable amount of screenings.
3. It permits the burning of egg or stove size anthracite, coke or any of the many kinds 40 of soft coals with a heavy banking of buckwheat.
4. It acts as a self feeder until the flow of coal stops, as shown by the dotted line from the feed door to below the baffle plate in 45 Fig. 1.
5. It provides at all times a hot spot directly back of the baffle plate at the junction of the lower part of flow at the extreme bottom point which can be depended upon to 50 ignite all gases as they accumulate.
6. It does not require a blower of any kind thereby avoiding the formation of clinkers.
7. It permits the carrying of a very low fire in mild weather while rapidly bringing 55 it up if the weather changes to colder.
8. It permits the induction over and through the fire of all of the oxygen that the gases will take without cooling the fire, thereby getting considerably more value out of the coal 60 burned than with ordinary methods.
9. It allows for an extremely long burning gas travel as indicated by the arrows in Fig. 1.
10. The air over the top of the coal drives 65 the gases back and through the baffle plate

so as to be ignited by the hot spot which in turn sends the burning gases directly up the back wall of the plant. The burning gases are then spread out and travel under the bottom part of the first heating sections to the opening through the same, thereby getting all the value possible out of these gases. 70

11. The perforations in the baffle plate allow the gases as generated to enter over the hot spot, there to ignite, instead of accumulating on top of the fire and passing up the chimney as generally happens. 75

12. It allows the twist damper to be nearly closed, thereby retaining the heat from the burning gases in the combustion chamber and in between the plates as shown in Fig. 1. 80

13. It permits the firing of enough coal at one time in extreme cold weather to carry the fire from twelve to fifteen hours. During mild weather in spring and fall, the same firing of coal will carry from forty-eight hours to sixty hours. This pertains particularly to buckwheat size or smaller. 85

14. The baffle plate may be readily made of cast iron and when water-cooled, it will 90 not burn out.

15. It can be connected directly to the water supply in hot water plants, thereby giving the plant more heating surface. 95

I claim:

1. A furnace comprising a shell enclosing a firebox having an outlet passage only at the upper and forward portion thereof, a grate at the bottom thereof, and a perforated baffle plate positioned in spaced relation above said grate and in spaced relation forward of the rear portion of said shell. 100

2. A furnace comprising a shell enclosing a firebox, having an outlet passage only at the upper and forward portion thereof, a grate at the bottom thereof, a charging door at the upper front portion of said shell, and a perforated baffle plate positioned at a lower level than said charging door in spaced relation above said grate and in spaced relation forward of the rear portion of said shell. 105

3. A furnace comprising a shell enclosing a firebox having an outlet passage only at the upper and forward portion thereof, a grate at the bottom of said firebox, a charging door at the upper front portion of said shell, and a vertically extending baffle plate provided with a multiplicity of horizontally extending perforations and positioned at a lower level than said charging door in spaced relation above said grate and in spaced relation forward of the rear portion of said shell. 115

In testimony whereof I hereunto affix my signature.

JAMES W. CHRISTIE.
